UNITED STATES PATENT OFFICE.

ALFRED E. POLAND, OF MINNEAPOLIS, MINNESOTA.

CAR-COUPING.

SPECIFICATION forming part of Letters Patent No. 268,823, dated December 12, 1882.

Application filed July 3, 1882. (No model.)

To all whom it may concern:

Be it known that I, ALFRED EDGAR POLAND, a citizen of the United States, and a resident of Minneapolis, in the county of Hennepin and State of Minnesota, have invented 5 a certain new and useful Improvement in Car-Couplings, of which the following is a specification.

This invention relates to car-couplings; and 10 it consists in the construction and arrangement of parts, as hereinafter shown, and as specifically claimed.

In the drawings, Figure 1 is a side view, and 15 Fig. 2 is a plan view, of portions of the ends of two freight-cars, showing my improvements attached thereto. Fig. 3 is an end view of one of the cars. Fig. 4 is an enlarged sectional plan view of the couplings detached from the car and coupled together; and Fig. 5 is a similar view, showing them disconnected. Fig. 6 20 is a perspective view of one of the draw-bars and hook or jaw detached; and Fig. 7 is a view of one of the jaws or hooks detached, Figs. 4, 5, 6, and 7 being on the same scale.

25 A' A² are portions of two car-bodies; B, the trucks, and C the track, all arranged in the ordinary manner.

The main part of the coupling consists in a 30 cast-iron piece, D, suspended by straps a between side timbers, E E, at their front ends, and provided with a pivoted bar or rod, b, running back through a cross-timber or bulk-head, E', and with the usual spring or springs, e. The rod b thus forms the "draw-bar" of 35 the coupling.

Upon the forward ends of the casing D are 40 projecting bars g h, the bar g usually cast in one piece with the casing D and made straight, and the bar h usually formed of steel and bolted or riveted fast to the casing and with 45 its outer end curved outward, as shown; or both bars may be cast in one piece with the casing D, or both formed separately and bolted fast thereto. The bar g is larger and longer 50 than the bar h, as they serve the double purpose of bumpers and guides, as hereinafter shown. Between the bars g h, partially within the casing D, is pivoted at i a hooked or barbed jaw, F, held up against a pin or stop, 55 K, by a spring, m. By this construction, when two of these couplings come together, as shown in Figs. 2 and 4, the bar g of the first coupling will pass between the bar h and hook F of the second coupling, while the bar g of the

second coupling will pass between the bar h 55 and hook F of the first coupling, and the two hooks will interlock. The barbs on the hooks F will be of a length to allow some play between the ends of the bars g and the ends of the casings D, so that some end movement 60 will be allowed to the couplings in "slacking up" a train of cars.

Through the sides of the hooks F and bars g slots are formed to receive the ends of bars G. These bars G are adapted to be moved inward and outward by a lever, H', and set and held either inward or outward by a spring-dog, r, actuated by pressing the trip H² at the top of the car or lifting on the handle H³ from the ground, so that the bar G may be operated 70 either from the top of the car or from the ground. By forcing the bar G inward the opposing barb on the hook F will be thrown off and the cars uncoupled. Only one of the bars G need be moved to uncouple the cars; but by 75 having them upon all the couplings the cars may be uncoupled from either side or on top from either car.

It frequently happens that cars are required 80 to be pushed along without coupling, in which event one of the bars G is pushed inward and locked in that position, as shown in Fig. 5, so that the beveled rear edge of the bar G forms an incline over which the hooks F pass and re-pass without catching upon each other, so that 85 the cars may be "bumped" together without coupling.

One of the great advantages of the bars g h is that in turning short curves they hold the 90 hooks F against each other and prevent the cars uncoupling.

What I claim as new is—

1. In a car-coupler, casing D, having cast-iron bar g and curved steel bar h, in combination with hook F, pivoted therein, both bar g 95 and hook F having slots therein, substantially as and for the purpose set forth.

2. The casing D, draw-bar b, guide-bars g h, and hook F, in combination with lever G, substantially as and for the purpose set forth. 100

In testimony whereof I have hereunto set my hand in the presence of two subscribing witnesses.

ALFRED EDGAR POLAND.
